Jean Viven and
Gustave Bessière,
By:- B. Singier, Atty.

UNITED STATES PATENT OFFICE.

JEAN VIVEN, OF VILLEFRANCHE-DE-ROUERGUE, AND GUSTAVE BESSIÈRE, OF LEVALLOIS-PERRET, FRANCE.

FIREARM.

1,277,669.

Specification of Letters Patent. Patented Sept. 3, 1918.

Application filed May 18, 1917. Serial No. 169,592.

To all whom it may concern:

Be it known that we, JEAN VIVEN, residing at Villefranche-de-Rouergue, France, and GUSTAVE BESSIÈRE, residing at Levallois-Perret, France, citizens of the Republic of France, have invented new and useful Improvements in or Relating to Firearms, of which the following is a specification.

This invention relates to a device that can 10 be fitted to rifles, guns and, generally speaking, to any fire-arms, for the purpose of enabling them to discharge projectiles of a caliber and weight greater than those of the projectile suitable for the fire-arm to which 15 the device is fitted.

In the accompanying drawing:

Figure 1 shows in longitudinal axial section showing the application of the device to a rifle;

Fig. 2 is an axial section of a projectile of 20 large caliber converted into a time-fuse grenade;

Fig. 3 is a plan of the mechanism applicable to the large projectile for converting 25 it into a percussion grenade, and

Fig. 4 is a sectional elevation showing the development of the mechanism shown in Fig. 3.

On the end of the barrel 1 of the fire-arm 30 is mounted a part 2 which constitutes the essential part of the invention. The said part consists of a sheath with two bores, the smaller part 3 of which fits on the outside of the barrel 1, while the part 4 of the larger 35 diameter, coaxial with the first part and with the barrel of the fire-arm, forms a guide for the projectile 5 to be discharged.

The said projectile 5 is therefore guided by the sheath or sleeve 4 and is provided, 40 along its axis, with a hole 6 passing right through, the diameter of the said hole being practically equal to the caliber of the fire-arm used; it could be provided with one or more openings 7 intended to receive fuses or 45 detonators or other suitable means for producing or delaying explosion.

The projectile 5 to be discharged is placed in its sleeve 4; the fire-arm is charged with its cartridge or with its usual projectile, and 50 when it is suitably laid, the shot is fired in the usual manner.

The ordinary projectile propelled by the explosion of the powder, leaves the barrel 1 and passes into the orifice of the hole 6 of

the projectile 5 of large caliber. During 55 the time that the small projectile takes to pass through the said hole 6, it forms an obturator, and enables the gases inclosed in the chamber 8 situated between the end of the gun barrel and the bottom of the projectile, to act by their pressure on the base of the projectile 5 which is thus projected from the said sleeve 4 in the direction of the target.

Even after the orifice 6 has been uncovered by the ordinary projectile, the gases escape only with difficulty owing to the throttling with which they meet, and this results in a continuation of the thrust, and also in partial suppression of the noise of 70 the explosion.

Moreover, the small projectile, in passing with force through the orifice 6, imparts its own rotation to the large projectile 5, which contributes to accurate shooting.

In order to avoid leakages, the sleeve 3 of small diameter comprises at its inner end a shoulder 9 which engages with the edge of the barrel 1 and is provided in the center with a hole 10 larger in diameter than the 80 ordinary projectile, so that the latter can pass through it.

The described device can be fitted to any fire-arms, as described, and it can also be provided when manufacturing the weapon, 85 and either form one piece with its barrel, or be independent of the same, so as to obtain two different uses of a single weapon. When applied to small-arms such as rifles or revolvers, it makes it possible to discharge by 90 means of such arms any kinds of projectiles, such as bombs, rockets, signals, cables, etc.

The large caliber projectile 5 can be used as a time-fuse grenade or as a percussion 95 grenade.

The large caliber projectile shown in Fig. 2, is practically similar to that described, that is to say it consists of a cylindrical body 5 having an axial hole 6 which affords 100 passage to the small caliber projectile.

One of the end plates of the hollow body 5 is provided with a tapped lateral hole 7 into which is screwed a screw plug 11, in the interior of which is arranged a wick or 105 cord 12 intended to burn within a given time, and having a detonator 13 at one of its ends.

The interior of the body 5 is filled with an explosive material into which the detonator projects.

The primer 14 of the said device is placed, 5 as shown in Fig. 2, in a hole in the plug 11 normal to that in which the wick 12 is arranged, and opposite the said primer is arranged a percussion device 15 which consists of a bent metal blade, one of the 10 branches of which is pressed against the corresponding face of the projectile 5 by the screw plug 11.

It will be readily understood that when the small caliber projectile escapes from the 15 hole 6, it will force the percussion device 15 against the primer 14 which will be ignited, ignite the match or cord 12 which will explode the detonator 13 after expiration of a given time, and finally the projectile 20 5 will explode like an ordinary grenade.

It is sufficient to calculate correctly the length of the cord 12 in order to bring about explosion of the projectile only when it has reached its object.

25 The device shown in Figs. 3 and 4 makes it possible to convert the large caliber projectile 5 into a percussion grenade.

To that end, to the front face of the projectile is secured, by means of a screw 16, 30 a powerful spring blade 17 curved so as to fit the circular shape of the projectile. The said spring normally stands away from the flat face of the latter and is held cocked by means of a pawl 18 consisting of a rod 35 provided with a lateral recess of suitable shape with which engages the free corresponding hook-shaped end 19 of the spring 17, the tension of which strongly presses the said pawl into a recess 20 provided on 40 the flat face of the projectile.

The spring 17 is 45 provided near its free end with a percussion pin 21 which can strike a percussion primer 22, so that, when the projectile has reached its object, the pawl 18, by striking the ground, will be moved out of its position of equilibrium either by contact or by momentum, and will thus release the spring 17, the percussion pin 21 of which will strike the primer 22 in order 50 to explode the projectile 5.

It is necessary to provide the said arrangement with a safety device that would make

its manipulation safe during handling and transport.

The said safety device comprises a button 55 23 with three collars, arranged on the spring 17 provided laterally with a notch or recess for receiving it.

The bottom collar engages between the 60 cocked spring and the front face of the projectile 5. The said button is held in its recess by a double twisted brass wire 24 which passes diametrically over the front of the projectile and is attached to a small button 25 as shown in Fig. 3.

It will be understood that when the small caliber projectile is discharged from the gun, it will cut the wire 24 and so release the button 23 and disengage it from its recess 70 extending from the periphery of the spring disk, for the purpose of enabling the spring 17 subsequently to play the part hereinbefore explained.

Having now particularly described and ascertained the nature of our said invention 75 and in what manner the same is to be performed, we declare that what we claim is:

1. A device adapted to be fitted to the end of a barrel of a fire-arm, comprising an outer part of a caliber greater than that of the said fire-arm, arranged coaxial with the barrel of the said arm and forming a guide for a projectile provided with an axial hole affording passage to the usual projectile whereby the large projectile is 80 propelled and rotated and the noise of the 85 explosion reduced.

2. A device as set forth in claim 1, in which the large caliber projectile is fitted with a percussion device actuated by the 90 small caliber projectile as it escapes from the central hole in the conduit of the large caliber projectile, whereby a primer is fired which ignites a wick terminating at a detonator which in its turn brings about the 95 explosion of the explosive in the interior of the projectile.

In testimony whereof we affix our signatures in presence of two witnesses.

JEAN VIVEN.

GUSTAVE BESSIÈRE.
